United States Patent Office.

JAMES C. ARMS, OF NORTHAMPTON, MASSACHUSETTS.

Design No. 4,664, dated February 21, 1871.

DESIGN FOR A POCKET-BOOK TIP.

The Schedule referred to in these Letters Patent and making part of the same.

To all whom it may concern:

Be it known that I, JAMES C. ARMS, of Northampton, in the county of Hampden, and State of Massachusetts, have invented a new Design for a Pocket-book Tip, of which the following is a specification, reference being had to the accompanying drawing.

My invention consists of a metallic tip applied to the end of straps for pocket-books, porte-monnaies, diaries, and similar articles, as represented in the accompanying drawing,

In the drawing—

A represents the strap, and

B, the metallic tip applied thereto.

What I claim is—

The design for a metallic tip for pocket-book straps, herein shown and described.

JAMES C. ARMS.
